FREQUENCY DIVIDER

Charles J. Hirsch, Douglaston, N. Y., assignor, by
mesne assignments, to Hazeltine Research, Inc.,
Chicago, Ill., a corporation of Illinois

Application August 16, 1944, Serial No. 549,743

5 Claims. (Cl. 250—27)

1

The present invention relates to frequency dividers and, particularly, to such dividers wherein a relatively low-periodicity recurrent-pulse signal is derived from a higher-periodicity recurrent-pulse signal.

There are many applications where it is desirable to derive, by a process of frequency division, a relatively low-periodicity recurrent-pulse signal from an input recurrent-pulse signal of relatively high periodicity. Multivibrators or relaxation oscillators have heretofore been conventionally used for this purpose, the multivibrator generating the low-periodicity signal and having an operation synchronized by the high-periodicity input signal. There is the limitation and disadvantage with frequency dividers of this type that the periodicity of the derived signal must be integral with that of the input signal. There is the additional disadvantage for certain applications that the wave form of the derived signal does not necessarily correspond with that of the input signal, since the former is determined solely by the values of the circuit components of the multivibrator, and may require the use of additional wave-shaping circuits to conform the wave shapes of the two signals.

A frequency divider which avoids the last-mentioned disadvantage is disclosed in the copending United States patent application of Robert B. J. Brunn, Serial No. 524,078, filed February 26, 1944, entitled "Signal-translating system," now abandoned, and assigned to the same assignee as the present application. In this arrangement, the input recurrent-pulse signal is translated through a repeater device to a synchronizing circuit of a univibrator. A pulse of the input signal initiates a cycle of operation of the univibrator which thereupon deenergizes the repeater device during the remaining portion of the cycle of operation of the univibrator, thus preventing the application to the latter of any additional pulses of the input signal. After the univibrator has completed its cycle of operation, however, the repeater device becomes again energized to translate the next pulse of the input signal to the univibrator to initiate another cycle of its operation. The output recurrent-pulse signal of this system has a periodicity which is integral with that of the input signal.

It is an object of the present invention, therefore, to provide a new and improved frequency divider which avoids one or more of the disadvantages and limitations of prior devices of the type described.

It is an additional object of the invention to

2

provide a new and improved frequency divider which enables the attainment of a nonintegral frequency division from a higher-periodicity recurrent-pulse signal to a lower-periodicity recurrent-pulse signal.

It is a further object of the invention to provide a frequency divider of simplified and improved circuit arrangement wherein a recurrent-pulse signal of relatively low periodicity may be derived from a recurrent-pulse signal of higher periodicity, the former having an average periodicity which is nonintegral with that of the last-mentioned signal but a predetermined constant time or synchronous relationship therewith.

In accordance with the invention, a frequency divider comprises a first input circuit adapted to have applied thereto a high-periodicity recurrent-pulse signal, a second input circuit adapted to have applied thereto a periodic control signal having a periodicity substantially lower than that of the first-mentioned signal and nonintegral with respect thereto, and repeater means for combining these signals and responsive to the combined amplitudes thereof for repeating during each period of the control signal only a portion of the combined signals including only a limited number of pulses of the first-mentioned signal. The divider includes pulse-responsive means responsive to at least one selected pulse of the repeated pulses occurring during each period of the control signal for initiating a pulse of a recurrent-pulse signal and for thereafter rendering the pulse-responsive means unresponsive to any pulse repeated during the remaining portion of the period of translation of the combined signals following the one selected pulse. The frequency divider also includes a signal-translating channel coupled to the first input circuit and responsive to the last-mentioned recurrent-pulse signal for translating during each pulse thereof the first-mentioned signal to derive a recurrent-pulse signal having a predetermined time relationship with the first-mentioned signal but an average periodicity equal to that of the control signal.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete radiant-energy system illustrated as of the type

55 for locating and identifying a radiated-signal re-

flector, such as an aircraft or naval vessel, which embodies the frequency divider of the present invention in a particular form; and Fig. 2 graphically represents potential relationships occurring at selected points in the frequency divider of the Fig. 1 system and is used as an aid in explaining the operation thereof.

Referring now more particularly to Fig. 1, there is represented a circuit diagram, partly schematic, of a complete radiant-energy system of the type for locating and identifying a radiated-signal reflector, such as an aircraft or a naval vessel, which embodies the frequency divider of the present invention in a particular form. The system includes a radiated-signal reflector-locating system 10 coupled to an antenna 11, usually having a sharply directive characteristic. The system 10 essentially comprises a pulse-modulation system and includes a pulse-signal generator and transmitter for generating a pulse-modulated wave signal, which is applied to the antenna 11 for radiation thereby, and a receiver having an input circuit coupled to the antenna 11 and having an output circuit coupled to vertical-deflecting electrodes of a cathode-ray tube 12, as indicated by V. The system 10 applies the pulses of the pulse signal generated thereby as synchronizing pulses to a horizontal-scanning generator 9, which in turn supplies horizontal-scanning potentials to horizontal-deflecting electrodes of cathode-ray tube 12, as indicated by H, to provide horizontal scanning of the cathode-ray beam thereof, each horizontal-scanning line T being initiated by a modulation pulse applied to the transmitter of the system 10.

The pulse-signal generator of unit 10 is also coupled through a frequency divider 13, presently to be described in greater detail, to a modulation circuit of an identifying system 14. The latter includes a pulse-modulation transmitter, having the modulation input circuit mentioned and having an output circuit coupled through a single-pole double-throw switch 15 selectively to either of two antenna systems 16 or 17. The identifying system 14 also includes a receiver having an input circuit coupled through the same switch 15 selectively to either of the antenna systems 16 or 17 and an output circuit coupled to the vertical-deflecting electrodes of the cathode-ray tube 12, as indicated at V. The antenna systems 16 and 17 have sharply directive characteristics which partially overlap one another. To effect periodic and alternate selection of the antenna systems 16, 17, the movable contact of the switch 15 is operated by an electromagnet 18 which is energized from an alternating current source 19 having a frequency, for example, of 60 cycles per second. The recurrent-pulse output signal of unit 13 is also applied to a univibrator which is effective upon application of a pulse thereto to generate a pulse initiating with the synchronizing-pulse input of unit 20 and having a duration substantially as long as the saw-tooth duration of the scanning potential provided by unit 9. The pulse output of unit 20 is applied to unit 10 to cause the receiver of unit 10 to be inoperative during the period of each applied pulse. Alternate pulses generated by unit 20 are applied to unit 9 and added therein to the developed saw-tooth scanning potential for a purpose which will be explained more fully hereinafter.

It will be understood that the various units just described may, with the exception of the frequency divider 13, be of a conventional construction and operation, the details of which are

well known in the art, rendering a detailed description thereof unnecessary. Considering briefly the operation of the system as a whole, and neglecting for the moment the operation of the frequency divider 13 presently to be described, pulse-modulated wave signals are generated by the transmitter of the system 10 and are radiated by the antenna 11 to a distant radiated-signal reflector, for example an aircraft or naval vessel. Radiated-signal energy is reflected by the latter and a portion of the reflected energy is received by the antenna 11 and applied to the receiver of the locating system 10. The receiver suitably amplifies the received wave signal, derives and amplifies the modulation components thereof, and applies them to the vertical-deflecting electrodes of the cathode-ray tube 12.

The horizontal deflection of the cathode-ray beam of tube 12 is initiated by the modulation pulses applied to the transmitter of system 10 and varies linearly with time. The modulation components applied by the receiver of system 10 to the vertical-deflecting electrodes of tube 12 produce a vertical deflection P on the horizontal trace T. The distance of the vertical deflection P from an end of the trace T is indicative of the distance of the radiated-signal reflector from the locating system.

The pulse-modulation signal applied to the transmitter of system 10 is also applied to the frequency divider 13. This modulation signal is of the recurrent-pulse type having a relatively high periodicity and there is derived therefrom by the frequency divider 13 and applied to a modulation circuit of the identifying system 14 a lower-periodicity recurrent-pulse signal which is used to pulse-modulate a wave signal generated by the transmitter of unit 14. This pulse-modulated wave signal, which may be considered an interrogating signal, is radiated from one of the antenna systems 16 or 17, depending upon which of the antenna systems is selected at a given moment by the switch 15. The radiated wave signal is propagated to the distant radiated-signal reflector. If the latter is equipped with suitable transpondor equipment for receiving the interrogating signal and for replying thereto, the reply wave signal is received by the same antenna system which radiated the wave-signal energy and is applied to the receiver of system 14. The received wave signal is suitably amplified by the receiver and the modulation components thereof are derived, amplified, and applied to the vertical-deflecting electrodes of tube 12, preferably with opposite polarity to the modulation components applied to the vertical-deflecting electrodes of tube 12 from the locating system 10. The resulting vertical deflection P' produced on the horizontal trace T is directly below the deflection P and produces an indication by which to identify the distant radiated-signal reflector.

The periodicity of the recurrent-pulse signal which modulates the wave signal of system 10 is much higher than that of the recurrent-pulse signal applied from unit 13 to the identifying system 14. Illustrative values in this regard are 800 and 120 pulses per second for these signals. This permits what may be called an "interlacing" of the displays produced on the fluorescent screen of tube 12 by the locating system 10 and the identifying system 14. To this end, the recurrent-pulse signal developed in the output circuit of the unit 13 is applied to univibrator 20 to develop in the output circuit of the latter a recurrent-pulse signal having one pulse for each pulse of the sig-

nal applied to unit 20 and a pulse duration substantially equal to the saw-tooth duration of unit 9. The periodic-pulse output signal of the multivibrator 20 is used to perform two functions. The first of these is to reduce to zero the output of the receiver of system 10 upon the occurrence of each pulse of the signal applied to univibrator 20, the receiver remaining deenergized for an interval corresponding to a complete horizontal trace of tube 12. The second function of the periodic-pulse output signal of univibrator 20 is to effect a horizontal displacement of the trace of tube 12 by a small constant value upon the occurrence of alternate pulses of this signal. As will presently be explained in greater detail, there are two pulses of the periodic-pulse signal derived by unit 13 for each complete cycle of the alternating potential of source 19. The operation of the switch 15 under the control of the electromagnet 18 is such that the antenna systems 16, 17 are alternately connected to unit 14 during alternate half cycles of the potential of source 19, the connection of either antenna to unit 14 being maintained for a period sufficiently long for an interrogating pulse to be radiated to the remote transponder equipment and for the reply pulse to be received by the same antenna system.

As a consequence, the periodic horizontal displacement of the trace of tube 12 previously described has the effect of producing a small horizontal displacement between the vertical deflection P' produced by the operation of one of the antenna systems 16 or 17 and the vertical deflection P'' produced by operation of the other antenna system. The antenna systems 16 and 17 are rotatably supported about a vertical axis and, by virtue of their overlapping directional radiation characteristics, may be rotated until the vertical deflections P' and P'' have equal amplitude, at which time it is known that the position of the transponder equipment is normal to the axis of alignment of the antenna systems 16 and 17. This aids in correlating and identifying the response of an answering transponder equipment with one or more indications P produced on the screen of tube 12 by the operation of the locating system 10.

In the operation of the locating system 10, it is essential that each horizontal trace T of the tube 12 be initiated in timed relation to the moment of radiation of individual wave-signal pulses by the antenna 11. It is further essential for the coordinated operation of the locating system 10 and the identifying system 14 that the moment of radiation of individual wave-signal pulses by either of the antennas 16 or 17, depending upon which of these antennas is coupled by switch 15 to the identifying system 14 at a particular moment, occur in timed relation to the initiation of a corresponding trace T of tube 12. Otherwise the trace pattern, which essentially comprises the superposition of a large number of similar trace patterns produced each second of operation, tends to drift across the screen of tube 12 and the deflections P and P' or P'' produced on the trace T are not readily indicative of distance of the radiated-signal reflector. Further, it is important that the wave-signal pulses of the identifying system 14 shall occur in timed relation to alternate half cycles of the alternating potential of source 19 since this source controls the alternate connection of the antenna systems 16 and 17 to the identifying system 14.

It is the purpose of the frequency divider 13 to develop, from the high-periodicity recurrent-

pulse modulation signal of the locating system 10, a lower-periodicity recurrent-pulse signal which may be applied to a modulation circuit of the identifying system 14 and which has pulses bearing a predetermined constant time relationship to corresponding pulses of the modulation signal of unit 10 and one pulse for each half cycle of the alternating potential of source 19.

Referring now more particularly to the portion 10 of the system embodying the present invention, the frequency divider 13 includes a first input circuit comprising input-circuit terminals 21 adapted to have applied thereto from the modulation-signal generator of unit 10 a high-periodicity recurrent-pulse signal which may have, for example, a periodicity of 800 pulses per second, but may in operation drift or change in an unstable manner over a small range of, say, 775 to 825 pulses per second. The frequency divider 13 also includes a second input circuit comprising a resistor 22 adapted to have applied thereto a periodic control signal having a periodicity substantially lower than that of the signal applied to the input-circuit terminals 21 and nonintegral with respect thereto. For convenience, the signal applied to the input-circuit terminals 21 will hereafter be referred to simply as the "input signal," while the signal applied to the input-circuit resistor 22 will be called the "control signal." In particular, the control signal is applied to the resistor 22 from the alternating-potential source 19 through a transformer 23 having a center-tapped secondary winding 24 connected in a full-wave rectifier circuit which includes a 25 pair of two-terminal rectifier devices 25 and 26.

The frequency divider 13 also includes repeater means for combining the last-mentioned signals and responsive to the combined amplitudes thereof for repeating during each period of the control 30 signal only a portion of the combined signals including only a limited number of pulses of the input signal. In particular, the repeater means repeats only the portion of the combined signals which exceeds a predetermined amplitude level. 35 The wave form of the control signal and this predetermined amplitude level are so chosen that only a limited number of pulses of the input signal are repeated with substantial amplitude during each period of the control signal. This means 40 comprises a vacuum-tube repeater device 27 having a first pair of input electrodes, comprising a control electrode 28 and a cathode 29, coupled to the input-circuit terminals 21 of the divider 13 through a multivibrator 30 which is of conventional construction and may include two vacuum-tube repeaters having the input circuit of each 45 coupled to the output circuit of the other. This multivibrator is used as a frequency divider for convenience in reducing by one-half the periodicity of the input signal. The coupling circuit used between the input electrodes 28, 29 of the repeater 27 and the output circuit of the multivibrator 30 includes a series coupling condenser 31 and a shunt resistor 32 which have circuit 50 values so selected as to perform a differentiation of the recurrent-pulse signal developed in the output circuit of the multivibrator 30.

The vacuum-tube repeater 27 also includes a second pair of input electrodes, comprising the cathode 29 and a screen electrode 33, which are coupled through a condenser 34 to the control-signal input-circuit resistor 22. Biasing means is provided for the repeater 27 so to bias the latter that the signals electronically combined by this tube are repeated thereby only when the

combined signals exceed a predetermined amplitude level which is sufficiently high that only a limited number of pulses of the input signal are repeated with substantial amplitude during each period of the control signal. This biasing means comprises a cathode resistor 35 included in the cathode circuit of tube 27 and a resistor 36 which couples the ungrounded terminal of the cathode resistor 35 to a source of unidirectional potential, indicated as +B. The unidirectional bias thus developed across the cathode resistor 35 is applied to the control electrode 28 of tube 27 through the resistor 32 and is applied to the screen electrode 33 of tube 27 through a grid resistor 37. The anode of tube 27 is energized from a unidirectional potential source, indicated as +B.

There is also provided pulse-responsive means responsive to at least one selected pulse of the pulses repeated by vacuum tube 27 and which occur during each period of the control signal for initiating a pulse of a recurrent-pulse signal and for thereafter rendering the pulse-responsive means unresponsive to any pulse repeated during the remaining portion of the period of translation of the signals combined by tube 27 following the one selected pulse. This means comprises a multivibrator 38 of conventional construction, similar to that of the multivibrator 30, having an input circuit coupled through a condenser 39 to the cathode resistor 35. The values of the circuit components of the multivibrator 38 are so selected that, when the operation is controlled by input pulses thereto from tube 27, the recurrent-pulse signal developed in the output circuit thereof is of constant average periodicity equal to that of the control signal and has a pulse duration slightly greater than the period of the input signal. To this end, the values of certain of the circuit components of the multivibrator 38 are so selected that the multivibrator initiates a cycle of its operation upon the first of the repeated pulses of substantial amplitude applied to its input circuit and thereafter renders itself unresponsive to any repeated pulses during an immediately subsequent interval equal to a substantial portion of the period of the control signal.

The frequency divider 13 additionally includes a signal-translating channel coupled to the input-circuit terminals 21 and responsive to the recurrent-pulse signal developed in the output circuit of the multivibrator 38 for translating, during each pulse of the latter signal, the input signal to derive a recurrent-pulse signal having a predetermined time relationship with the input signal, but an average periodicity equal to that of the control signal. This means comprises a vacuum-tube repeater 40 having a first pair of electrodes including a control electrode 41 and a cathode 42 coupled through a condenser 43 to the input-circuit terminals 21 and a second pair of input electrodes including the cathode 42 and a screen electrode 44 coupled through a condenser 45 and a grid-leak resistor 46 to the output circuit of the multivibrator 38. A grid-leak resistor 47 is provided for the control electrode 41 of tube 40. The anode of the tube 40 is energized through a resistor 48 from a source of unidirectional potential, indicated as +B, and is coupled through a condenser 49 to the modulation input circuit of the system 14 and through the univibrator 20 to the control circuit of the system 10 and to the horizontal-scanning generator 9, as previously described.

Considering now the operation of the frequency divider just described, and referring to the curves

of Fig. 2, the high-periodicity recurrent-pulse input signal applied to the input-circuit terminals 21 of the frequency divider 13 is represented by curve *a* of Fig. 2 and consecutive pulses thereof are numbered from 1 to 8 for convenience in referring thereto. This signal is applied through the coupling condenser 43 to the control electrode 41 of vacuum tube 40, but is not repeated to the output circuit of the latter tube due to a negative-bias potential developed on the screen electrode 44 of this tube in a manner presently to be described. The input signal is also applied to the input circuit of the multivibrator 30 and alternate pulses thereof, for example pulses 1, 3, 5, 7, etc., initiate successive cycles of operation of the latter. The values of certain components of the multivibrator 30 are so selected, in a manner well known in the art, that the natural or free-running period of oscillation of the multivibrator is slightly longer than twice the period of the input signal. Further, certain of the circuit components have values so selected that the control electrode of the first tube of the multivibrator is positive for an interval slightly less than the period of the input signal, the control-electrode potential of this tube having the wave form represented by curve *b*. The anode potential of this first tube of the multivibrator is represented by curve *c* and is applied as a recurrent-pulse signal through the coupling condenser 31 to the repeater device 27.

As previously mentioned, the coupling condenser 31 and resistor 32 have values so selected that these circuit components differentiate the recurrent-pulse signal developed in the output circuit of the multivibrator 30, thus to develop and apply to the control electrode 28 of the tube 27 a symmetrical recurrent-pulse signal having a wave form represented by curve *d*. The vacuum tube 27 is so biased, however, by the potential developed across its cathode resistor 35 that the signal applied to its control electrode 28 is repeated by this tube only when its screen electrode 33 has applied thereto a potential positive with respect to its cathode 29.

As earlier mentioned, the potential applied to the screen electrode 33 of tube 27 is the control signal derived from the alternating current source 19 by the full-wave rectifier system comprising the transformer 23 and rectifier devices 25 and 26. This control signal is applied to the screen electrode 33 through the coupling condenser 34. As is well known, the latter establishes the electrical or equal-area axis of the control signal so that the potential as applied to the electrode 33 is as represented by curve *e* of Fig. 2 and may have a maximum positive value of approximately 150 volts. During the interval t_1 to t_2 , Fig. 2, when the screen electrode 33 is positive, the positive pulses of the recurrent-pulse signal applied to the control electrode 28 of tube 27 are repeated by this tube and are developed across the cathode resistor 35 thereof. It may be noted that the negative pulses of the signal applied to the control electrode 28 are not repeated to the output circuit of tube 27 since the unidirectional bias developed across the cathode resistor 35 and applied through the resistor 32 to the control electrode 28 is sufficiently large that tube 27 is biased to anode current cutoff in the absence of any signal on its control electrode 28 so that the negative pulses of the applied signal simply bias the tube 27 below anode current cutoff. The recurrent-pulse signal thus repeated by the tube 27 and developed across its cathode resistor 35 is represented by

curve *f* of Fig. 2. It is thus evident that the tube 27 effectively electronically combines the input and control signals and is responsive to their combined amplitudes for repeating during each period of the control signal only a portion of the combined signals including only a limited number of pulses of the input signal.

It will be apparent from the foregoing described operation that the pulses of this signal have a fixed time relationship with particular ones of the pulses of the input signal and have an average periodicity equal to that of the control signal. The signal repeated by tube 27 is applied through the coupling condenser 39 to the input circuit of the multivibrator 38. Each pulse of the repeated signal initiates a cycle of operation of the multivibrator and the values of the circuit components thereof are so selected, in a manner well known in the art, that the natural or free-running frequency of the multivibrator is at least slightly longer than the period of the control signal. Certain of the circuit components of the multivibrator 38 are so selected that the control electrode of the first tube thereof is driven to a positive potential for an interval slightly less than the period of the input signal, the potential applied to the control electrode of this tube thus being as represented by curve *g*. The anode potential of the second tube of the multivibrator 38 varies in the manner represented by curve *h* of Fig. 2 and the alternating component of this potential is applied through the coupling condenser 45 to the screen electrode 44 of the vacuum-tube repeater 40. The screen electrode 44 becomes conductive during each pulse of the signal applied to the control electrode 41, thus to charge the condenser 45 and develop across the resistor 46 a bias potential which biases the tube 40 to anode current cutoff in the intervals between the pulses of the signal applied to the screen electrode. Consequently, the vacuum-tube repeater 40 repeats to its output circuit the recurrent-pulse signal applied to its input electrode 44 only during each pulse of the recurrent-pulse signal applied to its screen electrode 44. It will be recalled that the control electrode of the first tube of the multivibrator 38 becomes highly negative just prior to the occurrence of a pulse of the input signal next succeeding the pulse which initiated a cycle of operation of the latter, as shown by curve *b*. Hence, the differentiated positive pulse of the recurrent-pulse signal developed by the condenser 31 and resistor 32 and repeated by the vacuum tube 27 so controls each cycle of operation of the multivibrator 38 as to cause the initiation of each pulse of the recurrent-pulse signal developed in the output circuit of the latter unit at a moment slightly preceding the occurrence of a pulse, for example the pulse numbered 4 in curve *a*, of the input signal. This conditions the vacuum-tube repeater 40 to repeat such pulses of the input signal to develop in the output circuit of this vacuum tube a recurrent-pulse signal of relatively low average periodicity equal to that of the control signal and having pulses thereof occurring synchronously with and of the same wave form as corresponding pulses of the input signal. The signal thus derived by the operation of tube 40 is represented by curve *i* of Fig. 2 and is applied through the coupling condenser 49 to the units 10 and 14 to effect the operation heretofore described.

While applicant does not intend to be limited to any particular circuit values in the embodiment of the invention described, there follows a

set of circuit values which are found to be particularly suitable for a frequency divider of the type shown in Fig. 1:

5	Resistor 22	ohms	235,000
	Resistor 32	do	47,000
	Resistor 35	do	100,000
	Resistor 36	megohms	2.2
10	Resistor 37	do	1.0
	Resistor 46	do	3.3
	Resistor 47	do	1.0

Periodicity of signal at input

terminals 21 ____ pulses per second 725-825

Frequency of source 19 ____ cycles per seconds 60

25 As previously mentioned, the multivibrator 38 is conveniently used to reduce by one-half the periodicity of the signal applied to the input electrode 28 of tube 27, as compared with that 30 of the input signal applied to the input-circuit terminals 21. It has the additional function of causing the pulses of the recurrent-pulse signal applied to the input electrode 44 of tube 40 to lead in point of time certain pulses of the input 35 signal, thus to condition tube 40 to translate all portions of each of these certain pulses. It will be apparent, however, that this multivibrator may, if desired, be replaced by a conventional univibrator or that the frequency divider of the invention may even be somewhat simplified by 40 omitting the multivibrator altogether, since neither of the functions performed by the latter are essential to the operation of the invention. Further, the multivibrator 38 may likewise be 45 replaced by a conventional univibrator. While unit 38 operates to generate a recurrent-pulse signal which controls the operation of the repeater tube 40, it will be apparent that the frequency divider of the invention may be further 50 simplified by omitting the latter tube and by directly utilizing the recurrent-pulse signal generated by the multivibrator 38 as the signal which is applied to the units 10 and 14 in the same manner and for the same purpose as the signal applied thereto from tube 40.

55 While the time scale for the curves of Fig. 2 is such that only two pulses are repeated by the vacuum tube 27 during each interval when its screen electrode 33 is positive, it will be apparent 60 that the operation described will be the same even though a larger number of pulses are translated by tube 27 during this interval. This is true for the reason that the multivibrator 38 initiates a cycle of its operation only on the first 65 one of such translated pulses of substantial amplitude. It will be evident, however, that where a relatively large number of pulses are translated by tube 27 during the interval mentioned, various arrangements may be utilized in 70 place of the multivibrator 38, or preceding the latter, whereby a selected translated pulse other than the first pulse of substantial amplitude may be utilized to effect the cycle of operation which conditions the vacuum tube 40 to translate desired portions of the input signal. For example,

conventional countercircuits may be utilized to count pulses from the first one translated and to initiate a cycle of operation upon the occurrence of a subsequent selected translated pulse.

It will be apparent from the above description of the invention that a frequency divider embodying the invention is adapted to provide a relatively high ratio of frequency division, and one in which the pulses of a derived recurrent-pulse signal have a predetermined time relation to corresponding pulses of an input recurrent-pulse signal, yet an average periodicity which is not integral with that of the latter.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A frequency divider comprising, a first input circuit adapted to have applied thereto a high-periodicity recurrent-pulse signal, a second input circuit adapted to have applied thereto a periodic control signal having a periodicity substantially lower than that of said first-mentioned signal and nonintegral with respect thereto, repeater means for combining said signals and responsive to the combined amplitudes thereof for repeating during each period of said control signal only a portion of said combined signals including only a limited number of pulses of said first-mentioned signal, pulse-responsive means responsive to at least one selected pulse of said repeated pulses occurring during each period of said control signal for initiating a pulse of a recurrent-pulse signal and for thereafter rendering said pulse-responsive means unresponsive to any pulse repeated during the remaining portion of the period of translation of said combined signals following said one selected pulse, and a signal-translating channel coupled to said first input circuit and responsive to said last-mentioned recurrent-pulse signal for translating during each pulse thereof said first-mentioned signal to derive a recurrent-pulse signal having a predetermined time relationship with said first-mentioned signal but an average periodicity equal to that of said control signal.

2. A frequency divider comprising, a first input circuit adapted to have applied thereto a high-periodicity recurrent-pulse signal, a second input circuit adapted to have applied thereto a periodic control signal having a periodicity substantially lower than that of said first-mentioned signal and nonintegral with respect thereto, repeater means for combining said signals and responsive to the combined amplitudes thereof for repeating during each period of said control signal only a portion of said combined signals including only a limited number of pulses of said first-mentioned signal, pulse-responsive means responsive to at least one selected pulse of said repeated pulses occurring during each period of said control signal for generating a periodic-pulse signal having an average periodicity equal to that of said control signal and a pulse duration shorter than the period of said first-mentioned signal, and a signal-translating channel coupled to said first input circuit and responsive to said generated periodic-pulse signal for translating said first-mentioned signal during each pulse of said generated

signal to derive a recurrent-pulse signal having a predetermined time relationship with said first-mentioned signal and an average periodicity equal to that of said control signal.

3. A frequency divider comprising, a first input circuit adapted to have applied thereto a high-periodicity recurrent-pulse signal, a second input circuit adapted to have applied thereto a periodic control signal having a periodicity substantially lower than that of said first-mentioned signal and nonintegral with respect thereto, repeater means for combining said signal and responsive to the combined amplitudes thereof for repeating during each period of said control signal only a portion of said combined signals including only a limited number of pulses of said first-mentioned signal, pulse-responsive means responsive to at least one selected pulse of said repeated pulses occurring during each period of said control signal for initiating a pulse of a recurrent-pulse signal and for thereafter rendering said pulse-responsive means unresponsive to any pulse repeated during the remaining portion of the period of translation of said combined signals following said one selected pulse, a vacuum-tube repeater having input electrodes coupled to said first input circuit and to said last-mentioned means to have applied thereto said last-mentioned recurrent-pulse signal, and means for so biasing said vacuum-tube repeater that said first-mentioned signal is repeated only during each pulse of said last-mentioned recurrent-pulse signal to derive a recurrent-pulse signal having a predetermined time relationship with said first-mentioned signal but an average periodicity equal to that of said control signal.

4. A frequency divider comprising, a first input circuit adapted to have applied thereto a high-periodicity recurrent-pulse signal, a second input circuit adapted to have applied thereto a periodic control signal having a periodicity substantially lower than that of said first-mentioned signal and nonintegral with respect thereto, repeater means for combining said signals and responsive to the combined amplitudes thereof for repeating during each period of said control signal only a portion of said combined signals including only a limited number of pulses of said first-mentioned signal, pulse-responsive means responsive to at least one selected pulse of said repeated pulses occurring during each period of said control signal for deriving a recurrent-pulse signal having an average periodicity equal to that of said control signal and a pulse duration less than the interval between the pulses of said high-periodicity signal, and a signal-translating channel coupled to said first input circuit and responsive to said last-mentioned recurrent-pulse signal for translating during each pulse thereof said first-mentioned signal to derive a recurrent-pulse signal having a predetermined time relationship with said first-mentioned signal but an average periodicity equal to that of said control signal.

5. A frequency divider comprising, a first input circuit adapted to have applied thereto a high-periodicity recurrent-pulse signal, a second input circuit adapted to have applied thereto a periodic control signal having a periodicity substantially lower than that of said first-mentioned signal and nonintegral with respect thereto, repeater means for combining said signals and responsive to the combined amplitudes thereof for repeating during each period of said control signal only a portion of said combined signals including only a limited number of pulses of said first-mentioned sig-

nal, pulse-responsive means responsive to at least one selected pulse of said repeated pulses occurring during each period of said control signal for deriving a recurrent-pulse signal having an average periodicity equal to that of said control signal but with each pulse of said derived signal advanced in point of time with relation to that corresponding pulse of said first-mentioned signal which it is desired to translate, and a signal-translating channel coupled to said first input circuit and responsive to said last-mentioned recurrent-pulse signal for translating with fidelity of wave form during each pulse thereof a pulse of said first-mentioned signal to derive a recurrent-pulse signal having a predetermined time relationship with said first-mentioned signal but an average periodicity equal to that of said control signal.

CHARLES J. HIRSCH.
